(57) CLAIM

The ornamental design for a sun protection article, as shown and described.

DESCRIPTION

FIG. 1 is a perspective view of my new design for a sun protection article;

FIG. 2 is a front view of the sun protection article shown in FIG. 1;

FIG. 3 is a one-half rotated back view of the sun protection article shown in FIG. 2;

FIG. 4 is a three-quarters rotated side view of the sun protection article shown in FIG. 2;

FIG. 5 is a one-quarter rotated side view of the sun protection article shown in FIG. 2;

FIG. 6 is an overhead view of the sun protection article shown in FIG. 2;

FIG. 7 is a one-half rotated overhead view of the sun protection article shown in FIG. 2; and,

FIG. 8 is a perspective view of the sun protection article shown in FIG. 1, in an environment of use.

The broken line showing of a human figure and surfboard is for the purpose of illustrating environment and forms no part of the claimed design. The broken line showing of straps is for the purpose of illustrating portions of the article and forms no part of the claimed design. The broken line showing of stitching is for the purpose of illustrating portions of the article and forms no part of the claimed design. The dot dash broken lines define the bounds of the claimed design and form no part of the claimed design.

1 Claim, 6 Drawing Sheets
